Primary Examiner—Sandra L. Morris*Attorney, Agent, or Firm*—Haugen and Nikolai, P.A.[57] **CLAIM**

The ornamental design for the merchandise cooler with transparent cover, as shown and described.

DESCRIPTION

FIG. 1 is a top, front and side perspective view of my new design for a merchandise cooler with transparent cover;

FIG. 2 is a side elevational view of the design;

FIG. 3 is a front elevational view of the design;

FIG. 4 is a rear elevational view of the design;

FIG. 5 is a top plan view of the design;

FIG. 6 is a bottom plan view of the design;

FIG. 7 is a top, front and side perspective view of an alternative embodiment of the design shown in FIG. 1;

FIG. 8 is a side elevational view of the alternative embodiment of the design;

FIG. 9 is a front elevational view of the alternative embodiment of the design;

FIG. 10 is a rear elevational view of the alternative embodiment of the design;

FIG. 11 is a top plan view of the alternative embodiment of the design; and,

FIG. 12 is a bottom plan view of the alternative embodiment of the design;

FIG. 13 is a top, front and side perspective view of a second alternative embodiment of the design shown in FIG. 7; and,

FIG. 14 is a top, front and side perspective view of a third alternative embodiment of the design shown in FIG. 1.
